UNITED STATES PATENT OFFICE

167,161

CHAIN FOR A WRISTBAND OR SIMILAR ARTICLE

Alfred Pinson, Stamford, Conn., assignor to Apex Accessories Co., Inc., Greenwich, Conn.

Application November 16, 1951, Serial No. 17,451

Term of patent 14 years

(Cl. D45—4)

To all whom it may concern:

Be it known that I, Alfred Pinson, a citizen of the United States, residing at Stamford, in Fairfield County, State of Connecticut, have invented a new, original, and ornamental Design for a Chain for a Wristband or Similar Article, of which the following is a specification, reference being had to the accompanying drawing, forming part thereof.

Figure 1 is a side elevation of a chain for a wristband or similar article embodying my new design;

I claim:

The ornamental design for a chain for a wristband or similar article, as shown.

ALFRED PINSON.
